United States Patent Office.

DANIEL ASHWORTH AND ROBERT B. EATON, OF WOBURN, MASSACHUSETTS.

Letters Patent No. 78,352, dated May 26, 1868.

IMPROVED APPARATUS FOR CONCENTRATING SULPHURIC ACID.

The Schedule referred to in these Letters Patent and making part of the same.

Be it known that we, DANIEL ASHWORTH and ROBERT B. EATON, of Woburn, in the county of Middlesex, and State of Massachusetts, have invented a new and useful Improvement in Apparatus for Concentrating Sulphuric Acids, of which the following is a full, clear, and exact description, reference being had to the accompanying drawings, making a part of this specification, in which—

Figure 1 represents a perspective view of the apparatus containing our improvements, and Figures 2 and 3 represent a cage for holding the retorts.

This invention is designed as an improvement upon an apparatus for which Letters Patent were granted to us on the 12th of March, 1867; and the invention or improvement consists in the employment of retorts through which the acids pass in the process of condensation, made either wholly of platinum, or of platinum and glass combined.

The invention also consists in conducting the steam or vapor from the retorts to the oil-of-vitriol chamber, for the purpose of heating or imparting steam to its contents, and thus dispensing with the use of steam from a separate boiler.

The invention also consists in the employment of a reservoir or vessel formed with a double casing, so arranged that the oil of vitriol will pass into and through the space formed by the double casing previous to its undergoing the process of concentration, and thus become heated by the concentrated acid in the inner portion of the said vessel, the concentrated acid being in an equal degree cooled by contact with inner casing of the said vessel or reservoir.

Referring to the drawings, A represents a chamber containing the oil of vitriol, B being the outer side, properly framed and supported. D is the base or floor on which the apparatus is placed. The furnace is placed at the front portion, F, of the apparatus, and the products of combustion pass underneath the series of retorts to the chimney, as described in the patent previously referred to.

a a' represent retorts, which may be made either wholly of thin platinum, or partly of platinum and partly of glass. When made entirely of glass, as described in our patent previously referred to, they are liable to break, and thus waste the contents. The platinum retorts may be made very thin, which will admit of their contents being very quickly and highly heated. The upper portion, a', of the retorts is made to fit within a groove or recess, formed in the lower portion, in which groove water may be placed, to form a water-lute, to prevent the escape of the gases or vapors from the retorts.

b b b represent retorts made of glass, and communicating with each other by means of straight tubes or by siphons, as shown.

c c' c'' are leaden pans, arranged as shown at the rear end of the flue F'. The bottom of the pan c extends below the one next to it, and through the lower portion of the said pan pass tubes or pipes, d, open at each end, and communicating with the flue-space so as to allow of the passage of the products of combustion through the said tubes, and thus expose the contents of the pan c to a greater heating-surface. The pans communicate one with the other by means of tubes at their upper edges.

From the upper portion of the retorts extend tubes e, which are connected at their upper ends with a larger tube, G. The tube G enters the chamber A near the top, into which is conducted the steam or vapor arising from the retorts, and thus serves to heat and supply steam to the said chamber, by which means the steam from a boiler, as usually employed, may be dispensed with.

Near the front portion of the apparatus, and below the level of the lowermost retort of the series, is a vessel or reservoir, I, which is constructed with a double casing, so as to leave a space between the two casings, the said space being entirely disconnected with the space in the inner portion of the vessel I.

In the centre of the vessel I is arranged an upright tube of glass, K, which is designed to be suspended, by means of a shoulder or edge at its upper end, to the cover of the vessel I, the lower end of the said tube being over an opening in the bottom of the vessel, but not in contact with it.

A tube, h, leads from the lowermost retort to the top of the glass tube K, and from the opening in the bottom of the vessel extends a tube, L, to the pan P.

From the lower part of the oil-of-vitriol chamber A extends a tube, H, that enters at its lower end into the space between the two casings of the vessel I. On the opposite side of the said casing, at its upper end, is a tube, M, also communicating with the said space, and leading to the pan e, at the rear of the apparatus.

The concentrated acid, after passing through the series of retorts, is conducted in a highly-heated state into the tube K, in the centre of the vessel I, and, filling the said inner compartment, passes out through the aperture in the bottom and the pipe L, to the receptacle P. At the same time the diluted oil of vitriol, in a cool state, passing through tube H, fills the space surrounding the inner compartment, and thus serves to cool the concentrated acid contained therein.

The heat of the concentrated acid, after the latter has passed through the series of retorts, is thus utilized in imparting heat to the oil of vitriol previous to its entering upon the process of concentration, and the concentrated acid will in an equal degree become cooled by contact with the inner casing of the reservoir I, and by the time it reaches the pan P, is in a condition to be put into the carboys for transportation.

Figs. 2 and 3 represent a cage or frame of metal, which is inserted in the openings over the furnace-flue, and is designed to hold the retorts for the greater security of the latter.

Single retorts made of platinum have been used in concentrating acids. These were required to be made of thick material, and are, consequently, quite expensive and cumbersome. The advantages of a series of platinum retorts, or those made partly of platinum and partly of glass, as in our present invention, consist in their comparatively low cost, the small retorts enabling us to use light or thin sheets of platinum in their construction, economy in the use of fuel, and a saving of labor.

Having thus described our invention, what we claim as new, and desire to secure by Letters Patent, is—

1. Conducting the steam or vapors from the retorts to the oil-of-vitriol chamber, for the purpose and in the manner substantially as described.
2. I claim cooling the concentrated oil of vitriol and heating the vitriol before its concentration, by passing the same around or through a vessel, I, constructed as described.
3. I claim constructing the pan e, with tubes or flues d, for the purpose specified.
4. I claim conducting the acid from one retort to the other, by means of siphons or tubes, as described.
5. I claim constructing the retorts of platinum, or partly of platinum and partly of glass, when the same are arranged in a series and communicate with each other, as set forth.

In testimony whereof, we have signed our names to this specification in the presence of two subscribing witnesses.

DANIEL ASHWORTH,
ROB. B. EATON.
